UNITED STATES PATENT OFFICE.

PAUL BROWN KLUGH, OF CHICAGO, ILLINOIS, ASSIGNOR TO THE CABLE COMPANY, OF CHICAGO, ILLINOIS, A CORPORATION OF ILLINOIS.

CONTROLLING DEVICE FOR MUSICAL-INSTRUMENT MECHANISMS.

No. 893,736.

Specification of Letters Patent.

Patented July 21, 1908.

Application filed July 26, 1907. Serial No. 385,693.

To all whom it may concern:

Be it known that I, PAUL BROWN KLUGH, a citizen of the United States, residing at the city of Chicago, in the county of Cook and 5 State of Illinois, have invented a certain new and useful Controlling Device for Musical-Instrument Mechanisms, of which the following is a specification, reference being had therein to the accompanying drawings.

10 My invention relates to pianos, organs, and similar instruments, and to mechanisms adapted to automatically play musical instruments, and has for its object to provide a simple device for controlling the action of 15 such instruments and mechanisms that may be conveniently located for easy manipulation by the fingers of the operator.

Another object of my invention is to provide a device whereby the operation of two 20 or more operable parts, or divisions of such instruments or mechanisms may be controlled either separately or collectively and whereby one or more of the controlled operable parts or divisions may be sustained in 25 either operative or inoperative position without interfering with the control of other operable parts or divisions by the device.

Figure 1 is a view of the forward edge of the key-table of an automatic-playing piano, 30 showing my device placed in a position convenient for manipulation and illustrating the manner of such manipulation when the hands of the operator are employed to operate the controlling devices usually incorporated in 35 such instruments. Fig. 2 is a view illustrating the preferred construction of my device in connection with one of a possible number of methods of applying operating power to movable expression-modifying parts of a 40 piano. Figs. 3 and 4 illustrate modifications in the construction of my device.

Continued effort to afford adequate expression-regulating means upon mechanical musical instruments has developed a difficulty in providing controlling devices therefor that may be conveniently operated without the demand of unusual skill or continued practice. With the desire to overcome this difficulty, I have devised a tilting tablet that 45 may be employed for suitably controlling any of a number of various well-known methods of expression regulation, among which are (1) movement of the hammer-rail, (2) movement of the string-dampers, and (3)

regulation of the power exerted by the automatic-playing mechanism.

The three noted methods for regulation of the expression are sometimes separated into individually operable divisions, and in such instance combinations may be effected in the simultaneous, successive, or alternate operation of the different divisions which may be controlled by my device, which I will now describe.

In the drawings, 1 represents the key-bed, 65 2 the keys, 3 the key-slip, 4 the automatic-playing controlling-devices, 5 the damper-retracting rod, and 6 the hammer-rail-lifting rod of the usual type of automatic-playing piano. As all of these parts may be constructed in any ordinary or other manner and are well known to those conversant with the art, description thereof is unnecessary.

Placed in a position at the forward edge of the key-bed 1 convenient for manipulation 75 by a finger of the operator, I provide a tilting tablet 10, which in my preferred form of construction is supported upon the upper ends of two vertical valve-operating plungers 11 and 12. These plungers rest respectively upon two valves 13 and 14, which are arranged upon the under side of the key-bed.

I prefer to fit the tablet 10 into a sinkage 9 which serves partly as a guide for the tablet and partly to assist in the convenient disposal of the device. For the purpose of retaining the tablet in this sinkage and in proper relation at all times with the ends of the plungers 11 and 12, I pivot to the tablet at 8 a plunger 18, which extends through 90 the key-bed and is fitted with a nut and noise-preventing washer at 19. I have shown other noise-preventing cushions applied at 10^a and 11^a.

The valves 13 and 14 are each provided 95 with one or more channels 31, which form a continuation of the tubes 28 and extend to and open out upon the upper surface of the valves. The valves are normally pressed upwardly against the under side of the key-bed 100 by the springs 15 and 16, respectively, and the ends of the channels are in such manner held closed. The springs, 15 and 16 supporting the mechanism are strong enough to close the valves securely but may be sensitive to the slightest touch.

The device may be easily and advantageously operated by the little finger as shown

in Fig. 1, thereby allowing the employment of the other fingers in manipulation of other controlling devices usually incorporated in this class of instruments.

5 It will be seen that alternative depression of the ends of the tablet 10 will serve to open one or the other of the valves 13 or 14 by means of the plungers 11 and 12, and simultaneous opening of both the valves may be effected by pressure upon the tablet at or near the center thereof, also, intermittent operation of one valve during the sustained open position of the other may be accomplished by sliding or rocking the finger towards or from the center of the tablet while continuing the downward pressure thereon.

25 designates a device for operating the hammer-rail lifting-rod 6, and the operation thereof is sufficiently familiar to those conversant with the art to render elaborate description unnecessary.

The device mentioned is connected by means of the tube 32 with a source of air-tension supply (not shown) and comprises a 25 motor pneumatic 26 adapted to be collapsed by the air-tension when connected therewith by movement of the valve 27. Valve 27 is operated upon inflation and deflation of the diaphragm pneumatic 27^a caused by the admission or exclusion of outside air in tube 28. Tube 28 extends from the controlling valve 13, which when closed excludes outside air and permits a vacuum therein, equal to and derived from that of the chamber over the 35 diaphragm through the vent 33. The diaphragm is thus situated between chambers under equal stress and therefore remains in balanced or inoperative position, and the valve 27 is drawn firmly down upon the 40 lower seat, allowing inflation of the power pneumatic 26 through the open upper valve-port.

Simultaneous with the movement of the valve 13 to open the tube 28 is the upward 45 movement of the diaphragm 27^a due to the reduction of the tension under the diaphragm, by such opening of the valve.

Upward movement of the diaphragm forces the valve 27 away from the lower and 50 against the upper seat, thereby connecting the pneumatic 26 with air-tension and excluding outside air, causing immediate collapse of the said pneumatic.

30 designates a similar device which may be provided for the operation of the damper-retracting rod 5, and further duplications may be employed for the operation of other mechanisms or divisions comprised in the instrument.

60 An important advantage gained through the use of the device which I have described consists of the fact that different combinations may be effected in the grouping of the controlling connections of the parts or divisions for control thereby, and when desirable

more than one of such devices may be employed to advantage, such as for instance when the parts have been separated into treble and bass divisions.

Although I have shown and described my device in connection with means for operating well known expression devices of an automatic playing piano, I am aware that other means than those shown and described may be employed to secure desired effects, and that other operating power than air-tension may be utilized; that the device may be installed in organs for controlling the operation of parts comprised therein, and would be especially adaptable for controlling the operation of automatic playing mechanisms, whether or not contained within the case of a musical instrument. I do not, therefore, wish to limit myself to the use of the device in connection with the particular construction herein shown, but

What I do claim and desire to secure by Letters Patent, is:—

1. In a musical instrument, operable parts and means for operating the said parts comprising a tablet arranged for finger-depression successively at its opposite extremities and simultaneously at both extremities.

2. In a musical instrument, operable parts and means for operating the said parts comprising a tablet arranged for finger-depression alternately at its opposite extremities and simultaneously at both extremities.

3. In an automatic musical instrument, the combination of means for varying the operation thereof and a controlling device for said means comprising a tablet arranged for finger-depression at its opposite extremities and simultaneously at both extremities.

4. In an automatic playing mechanism for musical instruments, operable parts and means for operating the said parts comprising a tablet arranged for finger-depression successively at its opposite extremities and simultaneously at both extremities.

5. In an automatic playing mechanism for musical instruments, operable parts and means for operating the said parts comprising a tablet arranged for finger-depression alternately at its opposite extremities and simultaneously at both extremities.

6. In a musical instrument, a plurality of plungers and a tablet arranged for finger-depression supported by the said plungers, whereby depression of the tablet at a point approximately over a certain plunger operates that plunger.

7. In a musical instrument, a plurality of plungers and an oblong tablet pivotally supported for bodily finger-depression with its end parts in operative contact with said plungers, whereby depression of either of its said end parts operates the plunger in contact therewith and depression of both end parts operates both of the plungers.

8. In a key-board musical instrument, in combination with a key-table and keys, a device extending partly above and partly within the key-table near the forward edge 5 thereof and forward of and below said keys comprising a pair of plungers extending vertically through said key-table and an oblong tablet supported above and by said plungers.
10. 9. In a key-board musical instrument, in combination with a key-table and keys, a plurality of vertical plungers extending through said key-table to be operated, an oblong tablet resting with each end part over 15 and in operative contact with one of said plungers and adapted upon depression at the ends to operate the plungers thereunder, a plunger pivotally connected to the tablet and extending through said key-table, and a re- 20 movable screw-nut adjustably secured upon the pivotally connected plunger, said plungers, tablet, pivotally-connected plunger and screw-nut comprising a device supported to extend partly above and partly within the 25 key-table near the forward edge thereof and below said keys.
10. In an automatic playing mechanism, the combination of means for varying the operation of the mechanism and a controlling 30 device for said means comprising a plurality of plungers and an oblong tablet supported at each end part by one of the plungers and adapted upon depression of either of the ends to operate the plunger thereunder.
35. 11. In an automatic playing mechanism, the combination of means for varying the operation of the mechanism and a controlling device for said means comprising a plurality of plungers and an oblong tablet supported 40 with each end part in operative contact with one of the plungers and adapted upon depression of either of the ends to operate the plunger proximate thereto.
12. In an automatic playing mechanism, the combination of means for varying the 45 operation of the mechanism and a controlling device for said means comprising a plurality of plungers and an oblong tablet supported with each end part in operative contact with one of the plungers and adapted upon de- 50 pression of either end to operate the plunger proximate thereto and when depressed at both ends to operate both of the plungers.
13. In a musical instrument, the combination of a table, vertical plungers extending 55 through said table, an oblong tablet resting with its end parts in operative contact with said plungers, a plunger pivotally connected to the tablet and extending through said table, and a removable and adjustable screw- 60 nut secured to the lower end part of the pivotally-connected plunger to prevent withdrawal from said table and thereby acting with said pivotally-connected plunger to retain said tablet in said operative contact. 65
14. In an automatic playing mechanism, the combination of a table, vertical plungers extending through said table, an oblong tablet resting with its end parts in operative 70 contact with said plungers, a plunger pivotally connected to the tablet and extending through said table, and a removable and adjustable screw-nut secured to the lower end part of the pivotally-connected plunger to prevent withdrawal from said table and 75 thereby acting with said pivotally-connected plunger to retain said tablet in said operative contact.

Signed at Chicago, Illinois, this sixth day of July, 1907, in the presence of subscribing 80 witnesses.

PAUL BROWN KLUGH.
